(57) **CLAIM**
 We claim the ornamental design for a hand vacuum, as shown and described.

DESCRIPTION

FIG. 1 is a left side elevational view of a hand vacuum showing our new design.

FIG. 2 is a front elevational view thereof.

FIG. 3 is a right side elevational view thereof.

FIG. 4 is a rear elevational view thereof.

FIG. 5 is a top plan view thereof.

FIG. 6 is a bottom plan view thereof.

FIG. 7 is a rear perspective view thereof; and,

FIG. 8 is a perspective view thereof taken from above.
